FLASHING STRUCTURE

Application filed July 23, 1928. Serial No. 294,631.

This invention relates to flashing, so-called, made of non-corrodible sheet metal such as copper, zinc, or the like, and used in brick or stone walls where there is tendency for water to seep through the wall and injure the ceilings and interior walls of the building, as, for instance, where a roof comes in contact with the walls or where a chimney shaft or other object comes through a roof.

5 It has heretofore been the practice to use flat sheet metal sections as flashing, the sections being soldered together at their end portions and being embedded in the mortar joints with their side marginal portions 10 folded up or down against a face of the wall, as may be required. One of the major disadvantages of such flashing, is that it weakens the bond between the bricks or stones where it is used, there being comparatively 15 little bond between the flat surfaces of the section and the mortar.

20 One of the objects of the present invention is to provide flashing which does not impair the mortar bond between the bricks or stones 25 where such flashing is used. This object is attained by providing the flashing with non-corrodible metallic keying material, as in the form of expanded metal lath, wire cloth or screening, chicken wire, or the like, which 30 serve to key or bond firmly with the mortar longitudinally and laterally. Preferably, the keying material overlies both faces of the flashing and is uniformly distributed 35 throughout the sections, so that a firm bond of the sections with the mortar is ensured.

Further features and advantageous details and combination of parts will appear from the following more complete description of certain embodiments of the invention 40 shown on the accompanying drawings, wherein

Figure 1 shows in perspective a section of flashing provided with expanded metal lath.

45 Figure 2 is a similar view of a fragment of the lath.

Figures 3 and 4 illustrate certain steps in the assembly of the section with the lath.

Figures 5 and 7, respectively, show perspective views of modified constructions, partly broken away.

50 Figure 6 represents a fragmentary section through another modification.

Figure 8 represents a section through a wall in which the flashing of the present invention is used.

55 Referring in detail first to Figure 1 of the drawings, 1 represents a section of flashing made of suitable non-corrodible imperforate sheet metal such as copper, which constitutes the base portion. This metal base has a 60 series of pleats 2 formed transversely thereof and defining a series of transverse zones of metal 3, arranged in parallel planes, the zones lying alternately in the upper and lower planes. Associated with each zone is 65 non-corrodible, metallic keying material, which may take the form of sections of expanded metal lath 4, held in place at their side marginal portions by engagement in the folds of the pleats 2. These sections lie 70 above and under the faces of the alternate zones, and are located in planes intermediate the planes of the alternate zones. Such a uniform distribution of the lath throughout the entire base ensures a firm bond of the 75 flashing with the mortar and is particularly advantageous in that it requires a minimum amount of metal lath, which is retained in place only by the material of the base. The lath, which is, as stated, non-corrodible, may 80

consist of the ordinary expanded metal lath coated with a protecting layer of lead. One end portion 6 of the base 1 of the flashing is preferably formed for overlapping engagement with the corresponding end portion of 85 a similar flashing or section thereof, being shown provided with a transverse rib 7 of triangular form, which is adapted to take over a complementary rib 8 formed in an adjacent section, as shown in Figure 8.

In making the section described, a flat blank of suitable sheet metal of the desired dimensions may be drawn or shaped to a form comprising transverse zones of metal 5, set off alternately on different parallel planes by wall portions 10, which, as shown in Figure 3, preferably rise alternately at supplemental obtuse and acute angles from the zones of metal at the lower plane to the 10 zones of the upper plane. Sections of lath 4, which are of sufficient width to overlie the zones, are then applied to the upper faces of the lower zones of metal and the under faces of the upper zones of metal, being held 15 from falling out during handling at their side edges by the inclined wall portions 10. The section and lath thus assembled may then be pressed to produce a series of transverse folds 2 at the wall portions in which 20 the side marginal portions of the sections of lath are engaged, as illustrated in Figure 4. If desired, the flashing section may be flat and provided with metallic strand or ribbon material suitably fastened to both its faces. 25 For example, as shown in Figure 6, sections of metal lath 13 may be fastened as by spot-welding alternately on the upper and under faces of a flat flashing base 12 to produce a series of transverse bonding or keying zones. 30 Or, as shown in Figure 7, similar bonding zones may be produced by overlaying the base 12 with transversely extending wires or ribbons 15 hooked at their ends 16 to engage with the side edges of the section. 35 While we have described sections of flashing which are provided with metallic keying material to form a series of bonding zones alternately on the upper and under faces thereof, which ensure a uniformly firm bonding of the sections with the mortar, it is to be understood that both the upper and under faces of a section may be provided with such material, although in actual practice the constructions illustrated on the drawings, which 40 require the use of about half as much metallic keying material, have been found to be quite satisfactory.

Owing to the lack of a better generic term, by the expression "metallic keying material" 50 as employed in the appended claims, is meant any suitable keying material, such as expanded metal lath, wire cloth or screening, chicken wire, or the like, with which the mortar may be keyed to the flashing, 55 without the necessity of perforating the flashing or flashing base.

Having thus described certain embodiments of this invention, it will be evident to those skilled in the art that various changes 60 or modifications might be made therein without departing from the spirit or scope of the invention as defined by the appended claims.

What we claim is:

1. An article of manufacture consisting 65 of a section of flashing of non-corrodible,

imperforate sheet metal provided with metallic keying material which serves to key with the mortar where such flashing is used, said keying material being of the character of metal lath, wire cloth, chicken wire, or the like, whereby said flashing may be keyed to said mortar longitudinally and laterally. 70

2. An article of manufacture consisting of a section of flashing of non-corrodible, imperforate sheet metal provided with metallic keying material on both its faces, which serves to key with the mortar where such flashing is used, said keying material being of the character of metal lath, wire cloth, chicken wire, or the like, whereby said flashing may be keyed to said mortar longitudinally and laterally. 75

3. An article of manufacture, consisting of a section of flashing of non-corrodible, imperforate sheet metal provided with metallic keying material in a series of transverse zones alternately on its upper and under faces, said keying material being of the character of metal lath, wire cloth, chicken wire, or the like, whereby said flashing may be keyed to a bonding composition, such as mortar, both longitudinally and laterally. 80

4. An article of manufacture consisting of a section of flashing of non-corrodible, imperforate sheet metal provided with metallic keying material on its upper and under faces, said keying material being uniformly distributed substantially throughout the entire section, and being of the character of metal lath, wire cloth, chicken wire, or the like, whereby said flashing may be keyed to a bonding composition, such as mortar, both longitudinally and laterally. 90

5. An article of manufacture consisting of a section of flashing of non-corrodible, imperforate sheet metal carrying metallic keying material retained in place by folds in said flashing. 105

6. An article of manufacture consisting of a section of flashing of non-corrodible, imperforate sheet metal having a series of transverse pleats defining transverse zones of metal arranged in different planes, the zones lying alternately in the upper and lower planes, and metallic keying material lying above and under the faces of the alternate zones in planes intermediate the planes of the alternate zones, said material being held in place by engagement in the 110 folds of said pleats. 115

7. An article of manufacture consisting of a section of flashing of non-corrodible, imperforate sheet metal having a series of transverse pleats defining transverse zones of metal arranged in different planes, the zones lying alternately in the upper and lower planes, and metallic keying material lying above and under the faces of the alternate zones, said material being held in place 120 125 130

in the folds of said pleats, one end portion of said section being provided with a transverse rib adapted to take over a complementary rib of a similar section.

5 8. An article of manufacture consisting of a flashing base of non-corrodible, imperforate sheet metal, provided with sections of metal lath alternately on its opposite faces, said sections being distributed 10 substantially throughout the entire base.

In testimony whereof we have affixed our signatures.

SAMUEL H. COHEN.
JACOB WASSERMAN.
